UNITED STATES PATENT OFFICE.

JEREMIAH STEVER, OF BRIDGEPORT, CONNECTICUT, ASSIGNOR, BY DIRECT AND MESNE ASSIGNMENTS, TO THE BRIDGEPORT AUTOMATIC SAFETY LADDER AND HARDWARE COMPANY, OF SAME PLACE.

FIRE-ESCAPE.

SPECIFICATION forming part of Letters Patent No. 283,163, dated August 14, 1883.

Application filed February 10, 1883. (No model.)

To all whom it may concern:

Be it known that I, JEREMIAH STEVER, of Bridgeport, in the county of Fairfield and State of Connecticut, have invented certain new and useful Improvements in Fire-Escapes; and I do hereby declare the following to be a full, clear, and exact description of the invention, such as will enable others skilled in the art to which it pertains to make and use the same.

My invention relates to an improvement in fire-escapes, the object being to provide a flexible ladder and means for retaining it within small compass in the upper portion of a building and for releasing it from any story of the building.

A further object is to provide means for automatically checking the descent of the ladder.

20 A further object is to provide certain novel features of construction and arrangement of parts in a fire-escape to enhance its efficiency and facilitating its operation.

With these ends in view my invention consists in certain features of construction and combinations of parts, as will hereinafter be described, and pointed out in the claims.

In the accompanying drawings, Figure 1 is a view in side elevation of a portion of a building to which my improvement is applied. Fig. 2 is a rear view of the wall of the building, showing the arrangement of the different parts of the fire-escape. Fig. 3 is an enlarged view, in perspective, showing the automatic checking mechanism. Fig. 4 is a detached view, in vertical section, of the checking mechanism, showing the relative position of parts when the ladder is wound on its drum. Fig. 5 is a similar view, showing the relative position of parts when the ladder has been lowered. Fig. 6 is a view, in side elevation, of the drum and tripping mechanism. Fig. 7 is a detached view, in vertical section, of the housing for the weighted end of the ladder. Fig. 8 is a detached view of the tube for the operating cord or rod. Fig. 9 is a detached view of the links of the flexible ladder. Fig. 10 represents the

ladder-rounds and method of securing them in place.

A represents a drum, mounted in suitable 50 bearings, B, located at the top of a building and secured to the inside of the walls thereof. B' is a suitable shield partly encircling the drum.

To the shaft C of the drum, or any other 55 portion thereof, is secured one end of a flexible ladder, D, the outer or free end of which passes through a guideway, E. The guideway consists of the curved or inclined bottom, a, and sides b, which extend through the wall 60 of the building and in close proximity to the drum.

To the sides b is pivoted the upper end of a shield, c, the lower end of which is outwardly curved, as at d. This shield serves to 65 protect the end of the chain from rain and ice, and yet is automatically raised by the roller-weight attached to the lower end of the ladder when the latter is wound up on the drum. Ladder D is composed of the flat links 70 e, which are formed with end loops, e', and a narrow central connection, e''. The blank is bent back upon itself, thereby forming a single loop, e'', of the two end loops, e', and a loop, e'', of its central connection, e''. Another 75 blank is then inserted through the loop e'' and then bent back upon itself in the manner above described, and thus a chain, F, of any desired length, is formed. Two of these chains are united at suitable intervals by the ladder- 80 rounds G, which are preferably corrugated lengthwise, as shown, and their opposite ends slotted, as at f, within which slots are inserted a link of the chain, the round being secured by rivets f'. A chain of this construction is 85 especially adapted for the purpose of a flexible fire-escape ladder, because the links are flat and the chain quite flexible, thereby enabling the ladder to be wound into small compass and insuring its free winding on the 90 drum. Again, the ladder thus constructed is of great strength, is very light in weight, and hence answers admirably the purposes in view.

To the lower or free end of the ladder is con-

neeted a rolling weight, G', which insures the quick descent of the ladder, and also facilitates its automatic release. When the ladder is wound upon its drum, the roller G' comes in contact with the outwardly-flaring end of the pivoted shield, raising the latter and entering the guideway E, the weight being supported on the inclined bottom of the guideway. When the drum is released the roller-weight rolls down the inclined bottom, carrying the ladder with it to the pavement or the ground.

On one head of the drum A is secured a wedge or cam-shaped stop, H, with which engages an arm, h, on the trip-lever H', the latter being pivoted at the point h'. Lever H' is upheld by a spring, I, and is provided with a notch, i, in which engages a gravity-pawl, J, when the lever is drawn down. To one end of the drum-shaft is secured a crank, J', for winding the ladder upon the drum. In the operation of winding, the arm h of the trip-lever rides over the stop on the drum, while the ladder is prevented from unwinding by the arm h, engaging the heel j of the stop. To the trip-lever is connected a cord or rod, K, which extends downwardly through the small metal tube L, which may consist of sections of wrought-metal tubing screwed together and forming a closed guideway for the cord or rod K. This tube is slotted at any suitable place in the apartment of each story, as represented at l, through which slots project the handles M, which are secured to the cord or rod. By depressing any one of these handles the cord or rod K is depressed, thereby serving to retract the trip-lever and allow the drum to revolve and the ladder to fall to the ground. When the trip-lever is retracted or depressed sufficiently to disengage it from the stop on the drum, the gravity-pawl locks the trip-lever in its open position, this being done to insure the unwinding of the entire length of the ladder from the drum. Hence by a quick pull on the cord or rod the parts are locked in such a manner that the ladder will instantly unwind and fall to the ground. When it is desired to wind the ladder upon the drum, the pawl is disengaged from the notch in the trip-lever, thus allowing the latter to rise and engage the drum, as before explained. On the drum-shaft is placed a friction-disk, N, provided with a slot, n, in which engages a bar, N', that serves to prevent the rotation of the disk. The drum-shaft is screw-threaded, as at O, and carries a nut, P, having an arm, p, which engages with the bar N', and thus retains the nut against rotation with the drum-shaft. Between the nut and the friction-disk is placed a pawl-spring, Q. When the ladder is wound upon the drum, the nut P will be in the position illustrated in Fig. 4. When the drum is released, the screw feeds the nut toward the drum, and the parts are so constructed and arranged that when the ladder has nearly reached the pavement the nut will have com-

pressed the spring and forced the friction-disk against the drum with sufficient force to check the velocity of the drum, and thus check the descent of the ladder, and thereby prevent breakage of the ladder or other parts of the apparatus by a sudden shock or strain.

A building may be provided with any desired number of the fire-escapes, and, as the ladders are arranged in close proximity to the windows and may be easily operated from any floor of a building, they will afford quick and efficient means of exit from a burning building.

As it is evident that many slight changes in the construction and relative arrangement of parts might be resorted to without departing from the spirit of my invention, I do not limit myself to the exact construction and arrangement of parts shown and described; but

I would not have it understood that I am intending to claim, broadly, a device for automatically checking the descent of the ladder, since it has come to my knowledge that this, in its broad sense, has been heretofore accomplished. In the instance to which I refer a spiral spring was attached, at one of its ends, to the shaft of the drum, and at its other to a fixed nut, the coil of the spring being increased by the revolutions of the drum as the ladder neared the ground. Further, I am aware of the fact that chains have been constructed of the links employed by me in the construction of my improved flexible ladder; but by extended experiments and tests I have ascertained that a fire-escape ladder constructed in the manner herein shown and described, has special characteristics adapting it to the use in question. The ladder thus constructed is very light in weight and of great flexibility, and hence may be handled with a minimum outlay of power. Further, the ladder thus constructed is exceedingly strong and durable, and hence can be safely trusted for the purposes of a fire-escape.

Having fully described my invention, what I claim as new, and desire to secure by Letters Patent, is—

1. In a fire-escape, the combination, with a drum, a flexible ladder, and a friction-disk, of a traveling nut adapted to force the friction-disk against the head of the drum, substantially as set forth.

2. In a fire-escape, the combination, with a flexible ladder, a drum and friction-disk, of a screw-threaded drum-shaft, a traveling nut located thereon, and a spring interposed between the nut and friction-disk, substantially as set forth.

3. In a fire-escape, the combination, with a flexible ladder, a drum and friction-disk, of a traveling nut, a spring and means for preventing the rotary movement of the nut and disk, substantially as set forth.

4. In a fire-escape, the combination, with the chains, of corrugated ladder-rounds, substantially as set forth.

5. In a fire-escape, the combination, with the inclined stop H, secured to one side of the drum supporting the ladder, of the trip-lever H', provided with a projection, h, and notch i, the spring I, adapted to uphold said trip-lever, the pawl J, and means for depressing the trip-lever, substantially as set forth.

In testimony whereof I have signed this specification in the presence of two subscribing witnesses.

JEREMIAH STEVER.
